UNITED STATES PATENT OFFICE.

WILLIAM H. GRAY, OF BROOKLYN, ASSIGNOR TO THE GLEN COVE MACHINE COMPANY, (LIMITED,) OF GREEN POINT, NEW YORK.

PRESSER-BAR FOR PLANING-MACHINES.

SPECIFICATION forming part of Letters Patent No. 337,491, dated March 9, 1886.

Application filed January 13, 1886. Serial No. 188,443. (No model.)

To all whom it may concern:

Be it known that I, WILLIAM H. GRAY, of Brooklyn, in the county of Kings and State of New York, have invented a new and useful 5 Improvement in Wood-Planing Machines, of which the following is a specification.

My invention relates to that class of planing-machines in which are employed upright spindles carrying side-cutter heads for edging or 10 grooving boards or lumber. In such machines the upright spindles of the side-cutter heads are ordinarily supported in frames which are adjustable toward and from each other, and which are surmounted by head-plates, over 15 which the lumber passes as it is operated upon by the side-cutters. To these head-plates are ordinarily attached edge-guides for the boards, which are placed slightly rearward of the side-cutter heads, and to these edge-guides are ad- 20 justably secured top guides, under which the edge portion of the board or plank passes as it is subjected to the side cutters. When the lumber operated on is knurly or crooked in grain, the grooving which is performed by the 25 side-cutters is apt to be out of the center or crooked; and the object of my invention is to provide for properly holding the front end of the lumber down prior to the commencement of the grooving operation by the side-cutters, 30 and also to hold it down at a point beyond or rearward of the side-cutters.

The invention consists, essentially, in the combination, with the side-cutter heads and spindles and the head-plates above which the 35 cutter-heads operate, of top guides which are supported at their rear ends upon the head-plates, and which extend forward to or beyond the center of the side-cutter heads. Such forward extension of the top guides serves to hold 40 the board down prior to the commencement of the operation of the side-cutters upon it.

In the accompanying drawings, Figure 1 is an end view of such portions of a planing-machine as are necessary to illustrate my invention. Fig. 2 is a vertical section in a plane lengthwise of the machine, and Fig. 3 is a plan of corresponding portions of the machine. 45

Similar letters of reference designate corresponding parts in the several figures.

50 A A designate the two side-cutter heads,

which are supported upon the upright spindles B, and these spindles are journaled in bearings a, which are formed in or upon upright frames C. These upright frames C are surmounted by head-plates C', above which the cutter- 55 heads A operate.

I have not thought it necessary to show the lower portions of the side-cutter frames C, as they may be similar in construction and arrangement to the corresponding parts shown 60 in Letters Patent No. 315,406, granted April 7, 1885, to Gray and Hutchinson.

The frames C, which support the side-cutter spindles B, may be adjusted toward and from each other upon a bar, D, which extends trans- 65 versely to the machine, by screws, as shown in the aforesaid patent.

H H' designate the chip-breakers, which are employed in connection with the side-cutter heads A, and which are represented best in 70 Fig. 3. One of these chip-breakers, H, is adjustable by means of a screw and slot, b b', and is pivoted at b', as shown in the aforesaid patent. The other chip-breaker, H', is attached to the rear end of the side guide, I. 75

Upon the head-plates C C' are secured edge-guides E, which are best shown in Fig. 1, but also in the other figures, and to these edge-guides E are attached top guides, F, which overlap the upper side of the board or plank 80 at the edges, and serve to hold it down in proper position upon the bearing-surface c of the head-plate C'. As here shown, the top guides, F, are tongued and grooved into the adjacent faces of the edge-guides E, and are 85 adjustably secured by bolts d, passing through slots d' in them.

The novel feature in the construction of the top guides, F, consists in their being prolonged forward to a point at or beyond the center of 90 the cutter-head A, as is best shown in Figs. 2 and 3. The bottom surface of the top guides, F, is curved upward at their forward ends, as shown in Fig. 2, so as to enable the board or plank to enter readily beneath them and to 95 prevent its striking their forward edges.

In grooving knurly or crooked timber the grooves will sometimes not be straight in the edge of the plank or board, and the object in prolonging or extending the top guides for- 100

ward to a point at or beyond the center of the side-cutter heads A is to enable the forward end of the board or plank to enter beneath the top guides before the side-cutters commence 5 their operation upon its edges, and this construction of the top guides insures the straight grooving of such knurly or crooked timber.

I am aware that it is not new to employ in connection with top guides which are beyond 10 or rearward of the side-cutter heads separate top guides or foot-pieces which are attached to a bar on the top-cutter head; but this is objectionable, as the top-cutter head is sometimes strained by the operation of the top guides in 15 holding down the lumber. The extension of the top guides, which are supported at their rear ends upon the head-plates C', to a point at or beyond the center of the side-cutter heads enables the lumber to be properly held down 20 at the commencement of the grooving operation, and accomplishes this useful result with-

out any straining of the top-cutter head, as is liable to occur when separate top guides are attached to its cross-bar.

The top guides, F, may be considered as sup- 25 ported on the head-plates C', although they are directly attached to the edge-guides E.

What I claim as my invention, and desire to secure by Letters Patent, is—

In a wood-planing machine, the combination, with the side-cutter heads and spindles and the head-plates, above which the cutter-heads operate, of top guides, F, supported at their rear ends upon the head-plates and extending forward to or beyond the center of the 30 side-cutter heads, substantially as and for the purpose herein described.

WM. H. GRAY.
